UNITED STATES PATENT OFFICE.

JOSEPH R. TOURONGEAU, OF MARTINTON, ILLINOIS.

HEATER.

1,209,079.

Specification of Letters Patent. Patented Dec. 19, 1916.

Application filed March 31, 1916. Serial No. 88,031.

To all whom it may concern:

Be it known that I, JOSEPH R. TOURONGEAU, a citizen of the United States, residing at Martinton, in the county of Iroquois and State of Illinois, have invented new and useful Improvements in Heaters, of which the following is a specification.

This invention relates to heaters for automobiles and other motor-driven vehicles in which the heating medium is the exhaust of the engine.

The invention has for its object to provide a heater of this kind which is simple and efficient, and which is so constructed and connected up that it may be readily installed without making any alterations in the structure of the car.

A further object of the invention is to provide a heater which may also be employed 20 as a muffler cut-out.

The invention also has for its object to provide a heater which operates without noise.

Other objects and advantages of the invention will be pointed out in the detailed description appearing hereinafter, and in order that the same may be better understood, reference is had to the accompanying drawing, in which—

30 Figure 1 is a perspective view showing the application of the invention, and Fig. 2 is a sectional view thereof.

Referring specifically to the drawing, the heater is composed of a tube 10 of suitable 35 length so that it may extend across the floor of the car from one side to the other, the length of the tube therefore depending on the width of the car body. One end of the tube is closed, and the other end is open to 40 the atmosphere, said open end having an elbow 11 which extends downward when the tube is mounted in place.

Mounted lengthwise in the tube 10, in spaced relation therewith, is an exhaust conducting pipe 12 having side outlet perforations 13. This pipe is suitably fixed in the tube and extends throughout substantially the entire length thereof. To that end of the pipe which is at the elbow 11, is connected 50 a flexible tube 14 which delivers into the pipe the exhaust from the engine, the latter being indicated at 15 and its exhaust pipe at 16, the tube 14 being connected to the exhaust pipe in a manner to be presently 55 described.

Two heating units are shown, one for the

occupants of the front seat of the car, and one for the rear seat. It will, of course, be understood that this arrangement may be varied, and the invention is not limited to 60 any particular number of heating units.

To the exhaust pipe 16 of the engine 15 is connected the usual muffler 17. The exhaust pipe is tapped at a point between the engine and the muffler to obtain the heating medium 65 of the heating units. The connection between the exhaust pipe and the tubes 14 of the heaters is made by mounting over an opening 18 made in the exhaust pipe, a two-part coupling sleeve 19 having a lateral 70 branch 20 terminating in two branches 21 to which the tubes 14 are connected. In the branch 20 is a valve or damper 22 actuated by a lever 23 and a wire 24 extending to the front seat so as to be within easy reach of 75 the driver.

When the valve 22 is open, a portion of the exhaust passes through the tubes 14 into the pipes 12 from which it escapes through the perforations 13 into the heater tubes 10, the 80 latter being thus heated. The exhaust escapes to the atmosphere from the tubes 10 through the open ends thereof. The tubes 10 also operate as mufflers, and the heaters are therefore absolutely noiseless in opera- 85 tion.

The heater tubes 10 are mounted on the floor of the car in front of the seats, so as to be within easy reach of the feet of the occupants of the car. On one side of the car, 90 at 25, to accommodate the bends 11, the latter pointing downward to discharge the spent gases beneath the car.

The heaters can be easily regulated by 95 the valve 22, and the tubes 10 are quickly heated when the valve is opened. The perforations 13 distribute the hot gases throughout the entire length of the tubes, and the latter are thus uniformly heated.

100 The heating units can be readily removed upon disconnecting the tubes 14 from the coupling branches 21, and when this is done, the valve 22 will be kept closed so that there will be no escape of the exhaust, except by 105 the way of the muffler 17. The valve may also be opened to serve as a muffler cut-out, the exhaust thus escaping from the branches 21.

I claim:—

110 1. A heater for motor vehicles utilizing the exhaust of the engine comprising an

elongated tube closed at one end and having at the other end a laterally directed elbow which opens to the atmosphere, a pipe mounted lengthwise of the tube in spaced relation therewith and having outlet perforations thereinto, and an exhaust conducting tube connecting the pipe with the engine exhaust, said tube entering the first mentioned tube through the elbow in spaced relation with the interior thereof.

2. A heater for motor vehicles utilizing the exhaust of the engine, comprising an elongated tube closed at one end and having

at the other end a laterally directed elbow which opens to the atmosphere, a pipe 15 mounted lengthwise of the tube in spaced relation therewith and having outlet perforations thereinto, an exhaust conducting tube detachably connected at one end to the exhaust pipe of the engine, and at the other 20 end to the aforesaid pipe, said exhaust conducting tube entering the first mentioned tube through the elbow and in spaced relation with the interior thereof.

In testimony whereof I affix my signature. 25
JOSEPH R. TOURONGEAU.
